Primary Examiner — Jae Liang*Assistant Examiner* — Christopher Torma(74) *Attorney, Agent, or Firm* — Jiwen Chen; Joywin IP Law PLLC(57) **CLAIM**

An ornamental design for a height adjustable desk set as shown and described.

DESCRIPTION

FIG. 1 is a first perspective view of a height adjustable desk set showing the design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the height adjustable desk set and form no part of the design.

1 Claim, 6 Drawing Sheets(56)
